UNITED STATES PATENT OFFICE.

FRANK M. STOLL, OF DENVER, COLORADO.

FOLDING CAMP CHAIR.

1,422,319.

Specification of Letters Patent. Patented July 11, 1922.

Application filed July 1, 1921. Serial No. 481,827.

To all whom it may concern:

Be it known that I, FRANK M. STOLL, a citizen of the United States, and a resident of Denver, in the county of Denver and State of Colorado, have invented certain new and useful Improvements in Folding Camp Chairs; and I do declare the following to be a full, clear, and exact description of the same, such as will enable others skilled in the art to which it appertains to make and use my invention, reference being had to the accompanying drawings, and to the reference numerals marked thereon, which form a part of this specification.

My invention relates to back rests for chairs of the folding type more particularly used for camping purposes.

The principal object of my invention is to provide a back-rest of substantial construction for folding camp chairs of the type described in U. S. Letters Patent Number 1,157,795, patented October 26th, 1915, to Phillip J. Mix.

Another object of my invention is to provide a back-rest that while substantial will be resilient and yielding, thereby affording the maximum of comfort to the user.

A further object of my invention is to provide a back-rest that may be readily folded 30 with the chair proper and occupy a minimum of space.

In the use of my invention, many other objects and advantages embodied in the construction thereof will readily appear, and I 35 wish it understood that all such objects and advantages are anticipated and within the scope of my invention.

I will now proceed to describe my invention with reference to the accompanying 40 drawings which form a part hereof. Like numerals refer to like parts throughout the specification and in all views of the drawings.

In the drawings;

Figure 1, is a perspective view of a chair of the type described, having my improved back-rest extended for use.

Fig. 2, is a perspective view of the chair and back-rest folded ready for carrying.

Fig. 3, is a fragmentary detail view, showing the manner in which my improved back-rest is attached to the chair proper.

Fig. 4, is a cross section view taken on the line 4—4, Fig. 3.

Fig. 5, is a detail view of one of the chair supports, showing the manner of folding the back-rest supports thereon.

Fig. 6, is a plan view of the back-rest in its collapsed or folded condition.

Fig. 7, is a plan view of the chair and back-rest supports in the folded position.

Fig. 8, is a cross section view through one of the chair legs into which has been folded the back-rest supports; it is taken on the line 8—8, Fig. 7.

Let the numeral 10, designate the chair proper which is described in detail in U. S. Letters Patent Number 1,157,795, issued October 26, 1915 to Phillip J. Mix, chair 10, consists of four legs, each designated by the 70 numeral 11. Said legs are arranged, when extended, in pyramidal form and are all pivoted at their upper extremities to a block 12. Intersecting said legs 11 and pivoted thereto are four seat supports 13, arranged, 75 when extended, in the form of an inverted pyramid, being pivoted at their lower extremities to a common block 14, which is arranged directly below the block 12, and is connected therewith by means of a bolt 80 15, provided with a wing nut 16.

The seat of the chair 10 is designated by the numeral 17, and is of square shape and composed of leather, canvas or similar flexible material. Hooks 18 are riveted or otherwise fastened to each corner of the seat 17 and are adapted to engage in the upper extremities of seat supports 13. When wing nut 16 is revolved, the blocks 12 and 14 are drawn towards one another, thereby causing 90 the upper extremities of the four seat supports to move outwardly thus increasing the tension in the seat 17 and keeping it taut.

The above description will suffice to identify a type of chair to which my improved 95 back-rest may be applied.

Let the numeral 20 designate my improved back-rest in its entirety, consisting of two upright members 21 and 22, which are formed of channels, U shape in cross 100 section, which are connected near their upper extremities by strips 23. The strips 23 are formed of two parts of equal length, the parts being pivoted together at their inner

extremities as shown at 24', and to the upright members 21 and 22 at their outer extremities. When the back-rest 20 is folded, strips 23 overlap each other as shown in 5 Fig. 6.

Back-rest 20 is supported upon chair 10 by means of two back-rest supports 24 and 25, each of which consists of an upper member 26 formed of U shaped channel material and a lower member 27, formed of a solid rectangular bar. Member 27 terminates at its lower extremity in a curved neck 28 which passes through an opening 29 in one of the legs 11. The neck 28 has an 15 enlarged portion on the end thereof which prevents its withdrawal from the opening 29 after said opening has been closed around it. I have found that this form of pivot is more satisfactory and more easily 20 manufactured than the usual pin pivot.

Near the upper extremity of member 27 a slot 30 is formed in which a pin 31, fixed in the lower extremity of member 26, is arranged to travel. Back-rest supports 24 25 and 25 are supported near their upper extremities by means of rectangular yokes or collars 32, which are hinged near the outer end of the two rear supports 13 by means of hinges 33.

When extended for use members 26 and 27 of the back-rest supports 24 and 25 are in alignment, the pins 31 being in the lower ends of the slots 30, being rigidly held from any pivotal action by the U shaped members 35 26. Upright members 21 and 22 are slipped over the protruding upper extremities of the members 26. Ears 34 formed on members 21 and 22 extend within the collar 32, which supports the back-rest supports, and 40 wedge the joint rigid. Shoulders 35 formed on members 21 and 22, rest upon the collar 32, thereby preventing members 21 and 22 from sliding further over members 26. In the lower portions of members 21 and 22 and 45 in the upper portions of members 26 the open side of the U bar has been closed as shown in Fig. 4, forming hollow tubes.

When the weight of the person using the chair is brought against the back-rest, the 50 spring steel strips 23 bow outward conforming to the contour of the person's back. This bending is resisted by the elasticity of the chair itself as well as by the elasticity in the strips 23, thereby giving a resiliency to the back-rest that adds to the 55 comfort of the user.

In folding the chair, the back-rest 20 is removed from the back-rest supports 24 and 25 and folded as shown in Fig. 6; members 60 26 are raised until the pins 31 occupy the upper ends of the slots 30 as shown at 36, Fig. 5. Supports 24 and 25 can then be folded inward, as designated by the arrow 37 and shown in broken lines in Fig. 5,

until it lies within the U shaped leg 11 and 65 seat support 13 as shown by the full line position in Fig. 5. Collar 32 is then folded back as indicated by arrow 38, the upper extremity of member 26 being rounded for that purpose; this allows member 26 to fold 70 down over member 27 and within the hollow of leg as shown in Fig. 8. Seat supports 13 are then folded down into legs 11, as indicated by arrow 39, in Fig. 5, over the back-rest supports 24 and 25 into the hollow 75 U of legs 11, thereby forming a compact bundle as shown in Fig. 7.

The folded back-rest, as shown in Fig. 6, is placed with the folded chair, as shown in Fig. 7, and the whole wrapped with the seat 80 17 and tied by means of tapes 40, carried by the seat 17, as shown in Fig. 2. This forms a neat and compact bundle for carrying or storage.

Since the legs 11 and supports 13 extend 85 from the center outward towards the corners of the seat, yokes 32 and back-rest supports 24 and 25 also set at this angle. Upright members 21 and 22 are set on strips 23 at an angle to make it necessary to twist 90 them, bowing the strips 23 outward from the chair, in order to fit them over members 25 and 26. This twist is resisted by the elasticity of strips 23, causing members 21 and 22 to clamp to members 25 and 26 until 95 they are again twisted to remove them.

Having thus described my invention what I claim and desire to secure by Letters Patent is:

1. The combination with a chair of the 100 class described of a back-rest consisting of two upright members flexibly joined together by resilient means, adapted to be detached from said chair and collapsed, foldable supports for supporting said back-rest 105 on said chair, said foldable supports being adapted to fold within and simultaneously with said chair.

2. The combination with a folding camp chair of a back-rest formed of two upright 110 members detachably connected with said chair, pivoted means connecting said upright members and forming the back-rest proper, said upright members arranged to fold against and parallel with each other, supports for said back-rest consisting of members pivoted to the legs of said chair at their lower extremities and to back-rest supporting members at their upper extremities, said back-rest supporting members being adapted to fit, at their upper extremities, into said upright supports, means for locking said pivoted members to said back-rest supporting members when extended, means for detachably connecting said back-rest supporting members to the seat supports 125 of said chair.

3. The combination of a folding chair

having back-rest supports arranged thereon, a back-rest having two upright members arranged to fit over said back-rest supports, elastic strips connecting said upright members and tending to hold same at an angle differing from the angle of said back-rest supports, thereby causing them to exert a clamping action on said back-rest supports,

said clamping action serving to lock said back-rest to said chair.

In testimony whereof I affix my signature in the presence of two witnesses.

FRANK M. STOLL.
